UNITED STATES PATENT OFFICE.

LEWIS H. JOHNSON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed January 3, 1921. Serial No. 434,489.

To all whom it may concern:

Be it known that I, LEWIS H. JOHNSON, a citizen of United States, residing at Bloomfield, in the county of Essex, State of New Jersey, have invented certain new and useful Improvements in Telephone-Exchange Systems, of which the following is a full, clear, concise, and exact description.

This invention relates to a telephone exchange system and more particularly to a system in which connections are established by machine switching equipment.

In systems in which the control of automatic switches is effected by a central office sending mechanism through the transmission of revertive impulses from the switches to the sending mechanism, it is essential that the operations of the switching mechanism and office sending mechanism be kept in synchronism, in order that the switches shall be positioned accurately in accordance with the line designation which has been set up at the sender by the calling subscriber or operator. In such systems local district selectors are employed to extend connections to the proper district or office of the exchange and incoming and final selectors are employed in each district or office to further extend the connections to the terminals of the desired lines.

In accordance with the usual practice the incoming selector is controlled by a control relay which is connected directly into the interoffice trunk circuit extending back to the district selector, the trunk circuit forming part of a closed loop circuit, commonly known as the fundamental circuit, extending in the well known manner through the winding of the stepping or control relay of the sending mechanism. During the advance of the selector switch the stepping relay of the sender is operated by pulses transmitted to it over the fundamental circuit by the commutator of the switch until the sender is satisfied with respect to its particular setting, when the fundamental circuit is opened at the sender to render the control relay of the switch currentless whereby the advance of the switch is arrested. It is therefore apparent that the control relay of the switch must release immediately upon the satisfaction of the sender or upon the opening of the fundamental circuit at the sender, in order that

the switch shall not overrun and thus position its brushes upon the wrong group or set of terminals. 55

Where the districts or offices of the exchange are located adjacent each other or not exceeding twelve or thirteen miles apart, 60 the control relay of the switch functions quickly enough to provide accurate operation of the switch. If, however, the inter-office trunk comprises a cable of greater length, the control relay, by reason of the capacity charge upon the cable, has a tendency to release more slowly following the opening of the fundamental circuit at the sender. The interval between circuit opening at the sender and the release of the control relay of the switch, during operation over a cable thirty miles in length is substantially increased to three times the interval obtaining during operation over a cable two miles in length, which, added to the usual delay in arresting the movement of the switch, is sufficient to enable the switch-shaft to advance the brushes beyond the desired position. This tendency of the switch to overrun is more apparent during the 70 group selection movement of incoming selector and also since the final selector must be operated over approximately the same length of cable, applies equally well to the selective operation of the final selector 75 switch.

It is, therefore, the object of this invention to enable the accurate control of selector switches over long interoffice cable loops.

More specifically it is an object of this 90 invention to provide special controlling circuits for an incoming selector switch and to provide for repeating revertive impulses from a final selector switch to the office sending mechanism. 95

One feature of the invention resides in the provision of a sensitive line relay at the incoming selector switch adapted to be controlled over the interoffice trunk and which in turn controls the circuit of the usual control relay of the switch, and in the provision of a special commutator for governing the control relay of the switch and for transmitting revertive impulses to the office sender. 100

A further feature of the invention relates to the provision of means comprising a polarized relay at the incoming selector 105

switch for repeating revertive pulses transmitted from the commutator of the final selector switch to the office sender and for rendering the line relay of the incoming selector sensitive to the opening of the fundamental circuit at the sender.

Such other features of the invention as are contemplated by the present invention will become more apparent from the following 10 description and the appended claims.

The invention will now be described in connection with the accompanying drawings which disclose one specific embodiment of the invention. In the drawings, Fig. 1 15 shows the line of a calling subscriber, a diagrammatic illustration of a subscriber's individual line switch, a district selector, office sender, and so much of the circuits of the incoming selector switch as is necessary to disclose the present invention; and Fig. 2 shows the circuits of a final selector switch and the line of a called subscriber.

Inasmuch as the manner in which a connection is extended from the calling subscriber's line to the incoming selector switch, is not essential to an understanding of this invention, the circuits of the subscriber's line switch, district selector switch and office sender have been disclosed only diagrammatically. For a full disclosure of these circuits and the manner in which they function, reference may be had to the patent to F. A. Stearn and F. J. Scudder, No. 1,395,977, issued November 1, 1921.

35 The incoming selector switch shown in Fig. 1 and the final selector switch shown in Fig. 2 are of substantially the same type as disclosed in the aforesaid patent, being modified however for the purposes of this 40 invention.

The manner in which the system is organized will best be presented in connection with a description of the mode of its operation.

45 It will be assumed that the calling subscriber at station A desires to establish a connection with the line of subscriber B which line is located at a distant office of the exchange. To initiate the call, the calling subscriber removes his receiver from the switch-hook whereupon the individual line switch 100 functions in the well known manner to extend a connection from the calling line to the district selector switch illustrated 50 at 101. The calling subscriber then operates his impulse dial S in accordance with the designation of the desired line to set the registers (not shown) of the office sender 102. Following the setting of the registers of the 55 office sender, the sender functions in the well known manner in accordance with the office code which has been set up upon the code registers of the sender, to set the brushes of the district selector switch 101 upon the terminals of an idle interoffice trunk 103 ex-

tending to the particular office of the exchange in which the line of the desired subscriber terminates.

Upon the extension of the connection to the interoffice trunk 103, which terminates 70 in an incoming selector switch 104, the sequence switch (not shown), associated with the district selector, advances into position 10 and a fundamental circuit is established extending from the office sender 102 which 75 may be traced from battery, through the lower contact of cam 105, resistance element 133, the left-hand winding of line relay 106, the left-hand contact of cam 107 (1 to 8), the tip conductor of the interoffice trunk 103, 80 bank terminal 108, and brush 109 of the district selector switch, the right-hand contacts of cam 110 associated with the sequence switch of the district selector, conductor 111, the armature and back contact of the 0' 85 counting relay 112 of the office sender, the contact of cam 113 associated with the sequence switch (not shown) of the office sender, the windings of the sender stepping relay 114, conductor 115, the lower left-hand 90 and upper right-hand contacts of cam 116 associated with the sequence switch of the district selector, brush 117, and bank terminal 118 of the district selector switch, the lower right-hand contact of cam 119 (17 to 95 8), and thence to ground at the right-hand contacts of cam 120 (9 to 7).

The sender stepping relay 114 and the line relay 106 of the incoming selector switch energize in this circuit, the sender stepping 100 relay preparing a circuit in the well known manner for counting relays of the sender and the line relay 106 of the incoming selector, closing a circuit for the control relay 121 of the incoming selector. The circuit of relay 121 may be traced from battery, through the left-hand winding of this relay, the lower right-hand and upper left-hand contacts of cam 122, the armature and front contact of relay 106, and thence to 110 ground at the lower right-hand contact of cam 120. Relay 121 upon energizing in this circuit, closes a circuit for advancing sequence switch 123 out of position 1 and under the influence of master cam 124, into 115 position 2. This circuit may be traced from battery, through the magnet winding of sequence switch 123, the lower contact of cam 125 (1), and thence to ground through the left-hand armature and front contact of relay 121. As soon as sequence switch 123 leaves position 1, the initial energizing circuit of relay 121 is opened at the lower right-hand contact of cam 122, and a holding circuit is established for relay 121, which 120 may be traced from battery, through its left-hand winding, the contacts of cam 126 (17 to 11), the right-hand armature and front contact of relay 121, the upper contacts of cam 122, the armature and front 125 contacts of cam 126, the right-hand armature and front contact of relay 121, the upper contacts of cam 122, the armature and front 130 contacts of cam 126.

contact of relay 106, and thence to ground at the lower right-hand contact of cam 120 (9 to 7).

With sequence switch 123 in position 2 and relay 121 energized, a circuit is established for the up-drive magnet 127 which may be traced from battery, through the winding of magnet 127, the lower contacts of cam 128, and thence to ground at the left-hand armature and front contact of relay 121. Under the influence of magnet 127, the depending portion of switch shaft 129 is pressed against the constantly rotating up-drive drum 130 and the switch shaft is driven upwardly in its brush selecting movement.

As the switch shaft reaches its first brush selective position, the shaft wiper 131 engages a conducting portion of the commutator segment 132, whereupon a circuit is established in shunt of the windings of the sender stepping relay 114, which may be traced from battery, through the lower contact of cam 105, resistance element 133, the left-hand winding of line relay 106, the lower contact of cam 107 (13/4 to 2), conductor 134, commutator segment 132, shaft wiper 131, the left-hand contacts of cam 128, and thence to ground at the left-hand armature and front contact of relay 121. In response to the establishment of this shunt circuit, the sender stepping relay 114 becomes deenergized and in the well known manner causes the energization of one of the counting relays of the sender. Line relay 106 is, however, maintained energized over the shunt circuit. It is to be noted in this connection that commutator segment 132 is so placed with respect to the wiper 131, that the wiper 131 will engage a conducting portion of the commutator segment at a period sufficiently in advance of the positioning of the brushes of the switch with relation to a set of bank terminals, and sufficiently in advance of the engagement of holding pawl 135 with a notch in the depending portion of the switch shaft 129, to insure that the switch shaft shall not overrun in case the fundamental circuit is opened at the sender at the time the shaft wiper 131 engages a conducting portion of the commutator segment 132.

As the switch shaft 129 continues in its upward movement the wiper 131 engages an insulating portion of the segment 132, and the previously traced shunt circuit is opened whereupon the stepping relay of the sender again energizes and causes the circuits of the sender to function in the well known manner. In a similar manner as the switch shaft 129 moves upwardly the sender stepping relay 114 is intermittently deenergized and energized until the setting of the sender with respect to incoming brush selection is satisfied and the No. 0' counting relay 112

is energized to open the fundamental circuit.

Upon the opening of the fundamental circuit by the counting relay 112, the previously traced circuit, through the line relay 106 at the incoming selector, is opened and since 70 the left-hand energizing winding of relay 106 is of low resistance, relay 106 deenergizes as soon as shaft wiper 131 engages the next insulating portion of commutator segment 132. The provision of the low resistance 75 energizing winding on relay 106 permits the cable capacity in the interoffice trunk to charge very quickly through this winding, so that relay 106 is not rendered sluggish to deenergize by reason of such charge 80 through its winding.

Upon the deenergization of relay 106, the previously traced circuit for relay 121 is opened at its armature and front contact and relay 121 immediately deenergizes to 85 open the circuit of the up-drive magnet 127 to arrest the upward movement of the switch shaft. At its left-hand armature and back contact relay 121 closes a circuit for driving sequence switch 123 out of position 2 and 90 into position 3, this circuit extending from battery, through the magnet winding of sequence switch 123, the upper contact of cam 125 (2), and thence to ground at the left-hand armature and back contact of relay 95 121.

With sequence switch 123 in position 3, a circuit is established for the trip magnet 136 which may be traced from battery, through the winding of this magnet, and 100 thence to ground through the lower contacts of cam 137 (3 to 4). The trip magnet 136 upon energizing, rotates the tripping spindle 138 to position a tripping finger in association with the tripping cam (not shown) 105 of the selected set of brushes preparatory to tripping the selected set of brushes upon a subsequent upward movement of the switch shaft.

As soon as the sequence switch reaches position 3, the previously traced fundamental circuit is again established through the windings of sender stepping relay 114, and the left-hand winding of line relay 106, and the previously traced energizing circuit of 110 relay 121 is again established through the lower right-hand contact of cam 122 (3), the upper left-hand contact of cam 122 (9 to 4), and thence to ground at the lower right-hand contact of cam 120, and relay 121 upon 115 energizing establishes the previously traced circuit for advancing sequence switch 123 into position 4. With sequence switch 123 in position 4, the previously traced locking circuit is established for relay 121 and the circuit of the up-drive magnet 127 is again 120 established.

Upon the energization of up-drive magnet 127, the switch shaft is again driven 125 upwardly in its group selection movement. 130

- As the selected set of brushes approaches its first group selection position, the shaft wiper 138 engages a conducting portion of the group selection commutator segment 139 and a circuit is established in shunt of the winding of sender stepping relay 114 which may be traced from battery, through the lower contact of cam 105 (9 to 4), resistance element 133, the left-hand winding of relay 106, the upper left-hand contact of cam 107, (1 to 8) the upper contact of cam 140 (3½ to 4), conductor 141, commutator segment 139, shaft wiper 138, the left-hand contacts of cam 128, and thence to ground at the left-hand armature and front contact of relay 121. The sender stepping relay 114 being shunted, deenergizes and functions in the well known manner, but line relay 106 is maintained energized over the shunt circuit. As the switch shaft continues in its upward movement, the wiper 138 engages an insulating portion of commutator segment 139 and the previously traced shunt circuit is opened, whereupon the sender stepping relay 114 again energizes. In this manner as the switch shaft continues in its upward movement the sender stepping relay 114 is intermittently deenergized and energized until the sender is satisfied with respect to its incoming group selection setting or until the No. 0' counting relay 112 energizes to open the fundamental circuit.
- As soon following the opening of the fundamental circuit as the shaft wiper 138 engages the next insulating portion of the commutator segment 139, line relay 106 becomes deenergized and opens at its armature and front contact the circuit of control relay 121. To insure that relay 121 shall not deenergize to arrest the upward movement of the switch shaft until the brushes have been properly centered upon the first set of terminals in the selected group, relay 121 is maintained energized over a locking circuit which may be traced from battery, through its right-hand winding, the lower right-hand and upper left-hand contacts of cam 142, conductor 143, commutator segment 144, shaft wiper 145, the left-hand contacts of cam 128, and thence to ground at the left-hand armature and front contact of relay 121. As soon as the selected set of brushes has been properly centered upon the first set of terminals in the selected group, wiper 145 will engage an insulating portion of the commutator segment 144 and the maintaining circuit of relay 121 will be opened whereupon relay 121 deenergizes, opening at its left-hand armature and front contact the circuit of updrive magnet 127 to arrest the upward movement of the switch shaft and closing at its left-hand armature and back contact the previously traced circuit for advancing sequence switch 123 out of position 4 and into position 5.
- It is to be noted that the commutator segment 139 is placed at such a distance in advance of shaft wiper 138 that the circuit of relay 106 will be opened early enough to insure that the switch shaft shall not overrun in its selection movements and control relay 121 is maintained locked up over the centering segment 144 to insure that the switch shaft shall not underrun or become arrested in its movement before the brushes reach the proper set of bank terminals. With sequence switch 123 in position 5, a circuit is established for relay 121 which may be traced from battery, through the right-hand winding of relay 121, and thence to ground through the lower contacts of cam 142. Relay 121 upon energizing closes a locking circuit for itself extending through its left-hand winding, the contacts of cam 126, the right-hand armature and front contact of relay 121, the upper contacts of cam 137, and thence through the test brush 158 and to the grounded test terminal 159 upon which it is then resting if the first trunk of the selected group is busy. At its left-hand armature and front contact, relay 121 closes a circuit for advancing sequence switch 123 into position 6 and establishes the previously traced circuit extending through the winding of the updrive magnet 127.
- Upon the energization of magnet 127, the switch shaft is driven upwardly in its trunk hunting movement until the test brush 158 engages the test terminal of an idle trunk which it will be assumed is the trunk terminating in bank terminals 160, 161 and 162, when the previously traced locking circuit of relay 121 will be opened at test brush 158. Relay 121 is, however, maintained energized until the brushes are properly centered upon the bank terminals 160, 161 and 162, over a circuit which may be traced from battery, through the right-hand winding of relay 121, through the lower right hand and upper left-hand contacts of cam 142, conductor 143, commutator segment 144, wiper 145, the left-hand contacts of cam 128, and thence to ground at the left-hand armature and front contact of relay 121.
- Relay 121 upon deenergizing opens the circuit of the up-drive magnet 127 to arrest the upward movement of the switch shaft and at its left-hand armature and back contact closes the previously traced circuit for advancing sequence switch 123 into position 7. With sequence switch 123 in position 7, relay 121 is again energized over a circuit which may be traced through its left hand winding, the right-hand contacts of cam 122, and thence to ground through the left-hand contacts of cam 137. Relay 121 upon

- energizing closes at its left-hand armature and front contact a circuit for advancing sequence switch 123 into position 8, and also closes a locking circuit for itself which may be traced through its left-hand winding, the contact of cam 126, the right-hand armature and front contact of relay 121, the lower right-hand contact of cam 146 (6 $\frac{3}{4}$ to 18), brush 147 and bank terminal 161, conductor 148, the upper left-hand and lower right hand contacts of cam 200, resistance element 201, and thence to ground through the lower left-hand contact of cam 202 (1 to 8 $\frac{1}{2}$). Relay 121 is maintained energized over this circuit until the sequence switch 203 of the final selector 250 advances out of position 8 $\frac{1}{2}$, following the completion of the units selection movement of the final selector switch.
- With sequence switch 123 in position 8, the fundamental circuit is again established between the office sender and the line relay 106 of the incoming selector. The fundamental circuit may now be traced from battery, through the upper contact of cam 105 (7 to 8), the left-hand winding of relay 106, the upper left-hand contact of cam 107 (1 to 8), bank terminal 108, and thence as previously traced through the office sender, returning through bank terminal 118, the lower right-hand contact of cam 119 (17 to 8) and thence to ground through the armature and back contact of relay 151.
- Sender stepping relay 114 and line relay 106 energize in this circuit, line relay 106 establishing a circuit for the line relay 204 of the final selector switch, which circuit may be traced from battery, through the left-hand contact of cam 205 (1 to 10), the right-hand winding of relay 204, the lower left-hand contact of cam 206 (1), the lower left-hand contact of cam 207 (15 to 6), trunk conductor 208, bank terminal 162 and brush 149 of the incoming selector switch, the right-hand contact of cam 150 (8), the armature and front contact of line relay 106, the left-hand contact of cam 120 (8) the winding of polarized relay 151 and thence to grounded battery. It is to be noted that this circuit extends from battery to battery through the windings of relays 151 and 204, but the battery connected to the winding of relay 151 is of lower potential than the battery connected to the winding of relay 204, and therefore sufficient current flows over the circuit to cause the energization of relay 204. Relay 151, however, being polarized does not energize in this circuit to move its armature from its back contact.
- Relay 204 upon energizing establishes a circuit for relay 209 which may be traced from battery, through the left-hand winding of relay 209, the upper left-hand contact of cam 210, the left-hand armature and front contact of relay 204, and thence to ground at the upper contact of cam 211. Relay 209 upon energizing establishes a circuit for advancing sequence switch 203 out of position 1 and under the influence of master cam 212 into position 2. This circuit may be traced from battery, through the magnet winding of sequence switch 203, the lower contacts of cam 213, and thence to ground at the right-hand armature and front contact of relay 209.
- Relay 209 also establishes a locking circuit for itself extending through its left-hand winding, the armature and back contact of relay 214, the left-hand armature and front contact of relay 209, thence over sleeve conductor 215, bank terminal 160 brush 159, and to ground through the upper right-hand and lower left-hand contacts of cam 137.
- With sequence switch 203 in position 2 and relay 204 energized, a circuit is established for the high speed up-drive magnet 216 which may be traced from battery, through the winding of magnet 216, the lower contact of cam 217, (2) the left-hand armature and front contact of relay 204, and thence to ground at the upper contact of cam 211. In response to the energization of magnet 216, the depending portion of switch shaft 218 is pressed against the constantly rotating up-drive drum 219 and the switch shaft is moved upwardly in its brush-selecting movement. As the switch shaft approaches its first brush selection position, the shaft wiper 220 engages a conducting portion of the commutator segment 221 and a circuit is established for effectively energizing the polarized relay 151 which may be traced from battery, through the winding of relay 151, the lower left-hand contact of cam 120 (8), the armature and front contact of relay 106, the right-hand contact of cam 150, brush 149, and bank terminal 162, trunk conductor 208, the lower left-hand and upper right-hand contacts of cam 207, conductor 223, commutator segment 221, wiper 220 and thence to ground through the upper left-hand contact of cam 202.
- Relay 151 upon attracting its armature opens a shunt normally connected around the intermediate high resistance winding of line relay 106, which shunt may be traced through the intermediate winding of relay 106, the lower contacts of cam 119, and thence to ground at the armature and back contact of relay 151, and closed at the front contact of its armature a circuit for including the right-hand high resistance differential winding of relay 106 in series with the intermediate winding of the relay. This series circuit may be traced from battery, through the upper contact of cam 105, the right-hand winding of relay 106, the armature and front contact of relay 151, lower

contacts of cam 119, and thence to ground through the intermediate winding of relay 106. Upon the removal of the shunt from around the intermediate winding of relay 5 106, this high resistance winding is effectively connected into the fundamental circuit whereupon the current flowing over the fundamental circuit is reduced to such an extent that sender stepping relay 114 deenergizes.

10 As the switch shaft of the final selector continues in its upward movement the shaft wiper 220 engages an insulating portion of commutator segment 221, whereupon the previously traced energizing circuit of relay 15 151 is opened at shaft wiper 220 and relay 151 energizes in the opposite direction to retract its armature, reestablishing the shunt around the intermediate winding of relay 106, whereupon the current flowing over the 20 fundamental circuit is again increased to its normal value and stepping relay 114 again energizes. In this manner during the upward movement of the switch shaft 218, polarized relay 151 is intermittently operated 25 to thereby deenergize and energize the sender stepping relay 114 until the office sender is satisfied with respect to its hundreds or final brush selection setting when the No. 0' counting relay 112 becomes energized to open 30 the fundamental circuit.

It is to be noted in connection with the operation of relay 151 that this relay being polarized responds very quickly when current flows through its winding in one direction 35 by reason of a circuit through the shaft wiper 220 of the final selector switch and also when this circuit is opened at the shaft wiper of the switch, and that therefore the pulses transmitted from the final selector 40 switch are repeated to the office sender without appreciable delay.

As soon following the opening of the fundamental circuit at the office sender as the shaft wiper 220 engages the next insulating 45 portion of the commutator segment 221, thereby opening the circuit of polarized relay 151, the line relay 106 deenergized to open the previously traced circuit extending through the winding of relay 204 at the final 50 selector switch and relay 204 thereupon deenergized to arrest the upward movement of the switch shaft. It is to be noted that relay 106 is prepared for releasing immediately upon the opening of the fundamental circuit 55 at the sender regardless of the position of relay 151 as determined by the commutator of the final selector. If relay 151 has retracted its armature, relay 106 releases quickly since only its low resistance winding is connected to the fundamental circuit at this time. If the armature of relay 151 is attracted, the intermediate and right-hand high resistance windings of relay 106 are connected in opposition through the front 60 contact of polarized relay 151, and the cable 65

capacity in the interoffice trunk is thereby permitted to charge very quickly through the windings of relay 106 as soon as the fundamental circuit is opened at the sender, and the low resistance shunt is removed from 70 around the differential winding of the relay. Upon the deenergization of relay 204, sequence switch 203 is advanced into position 3 over a circuit which may be traced from battery, through the magnet winding of sequence switch 203, the upper contacts of cam 224, the left-hand armature and back contact of relay 204, and thence to ground at the upper contact of cam 211. With sequence switch 203 in position 3, the previously traced circuit extending through the windings of relays 204 and 151 is again established and relay 204 upon energizing advances the sequence switch 203 into position 4. With sequence switch 203 in position 4, the 75 final selector switch is controlled in the manner previously described in its group selection movement. Inasmuch as the final selector switch functions during its group selection movement in the well known manner, its operation will not be described in detail herein. The control of the final selector switch in its group selection movement, however, is more critical than its control during its brush selection movement, since the holding notches in the lower portion of the switch shaft 218 are more closely spaced and consequently any over-running of the switch shaft is more vital. To permit an earlier closing 80 of the circuit of relay 151, the conducting portions of the group selection segment 225 of the switch commutator, are widened downwardly. The upper edges of these conducting portions are maintained in the usual 85 position relative to the wiper 226 to insure the switch against under-running.

Following the group selection or tens selection movement of the final selector the sequence switch 203 advances in the well known manner into position 6, in which position the final or units selection movement of the switch shaft is controlled. This operation of the final selector switch and the subsequent functioning of the switch to 90 test the called line, proceeds in the well known manner.

Following the units selection movement of the final selector switch, sequence switch 203 is advanced out of position 8, whereupon the previously traced holding circuit of relay 121 is opened at the contact of cam 202. Relay 121 upon deenergizing closes at its left-hand armature and back contact a circuit for advancing sequence switch 123 out of position 8 and into position 9. With sequence switch 123 in position 9, a circuit is established through the left hand winding of line relay 106 and the control circuit office sender for causing the advance of the office sender for talking selection in the man- 100 105 110 115 120 125 130

ner fully set forth in the aforesaid patent to F. A. Stearn and F. J. Scudder. This circuit may be traced from battery, through the lower contact of cam 105, (9 to 4), resistance element 133, the left-hand winding of relay 106, the upper right-hand contact of cam 107 (9 to 10) thence as previously traced through the office sender and returning over terminal 108 to ground at the lower left-hand contact of cam 140 (9 to 10). Relay 106 energizes in this circuit and at its armature and front contact closes the previously traced circuit for relay 121, which upon energizing closes a circuit for advancing sequence switch 123 out of position 9 and into position 10.

Following talking selection the circuit for relay 106 is opened and relay 121 de-energizes advancing sequence switch 123 into position 11. With sequence switch 123 in position 11 a circuit is established over the interoffice trunk in the well known manner, through the lower right-hand contact of cam 140 (11 to 18) through the winding of relay 152, and the upper right-hand contact of cam 119, and relay 152 upon energizing establishes a circuit for relay 121 which may be traced from battery, through the left-hand winding of relay 121, and thence to ground at the armature and contact of relay 152. Relay 121 upon energizing closes a circuit for advancing sequence switch 123 out of position 11 and into the talking position 16. Inasmuch as the operation of applying ringing current to the line of the called subscriber is well known in the art, and since it is immaterial to an understanding of this invention, the ringing circuits associated with the incoming selector have not been disclosed or described herein.

Following the termination of the conversation between the calling and called subscribers, the calling subscriber restores his receiver to its switch-hook whereupon the line switch 100 and district selector switch 101 become restored in the well known manner. Upon the restoration of switch 101, the circuit of relay 152 is opened which in turn opens the circuit of relay 121. Relay 121 upon deenergizing closes at its left-hand armature and back contact the previously traced circuit for advancing sequence switch 123 out of position 16 into position 18. With sequence switch 123 in position 18 a circuit is closed for the down-drive magnet 153 which may be traced from battery, through the magnet winding the lower left-hand and upper right-hand contacts of cam 122, and thence to ground through the left-hand contacts of cam 137. Magnet 153 upon its energization presses the depending portion of the switch shaft against the constantly rotating down-drive drum 154, whereby the switch shaft is moved down-

wardly into its normal position. Upon reaching its normal position a circuit is closed for advancing sequence switch 123 into its normal position over a circuit which may be traced from battery, through the magnet winding of sequence switch 123, the contact of cam 155 (17 to 8), normal commutator segment 156, shaft wiper 138 and thence to ground at the contact of cam 157 (7 to 1). 75

As soon as sequence switch 123 leaves position 16 $\frac{1}{4}$, the circuit previously traced for maintaining relay 209 of the final selector switch energized, is opened at cam 137 and the restoration of the final selector switch is thereupon initiated. The final selector switch thereupon restores to normal position in the manner fully set forth in the aforesaid application. All of the circuits employed in the establishment of the connection are now in their normal condition. 80 85

What is claimed is:

1. In a telephone exchange system, a calling line, selector switches and a connecting circuit for extending a connection from said line, a sending mechanism for controlling said switches, a fundamental switch controlling circuit comprising said connecting circuit extending between said sending mechanism and said switches, means associated with one of said switches controllable over said fundamental circuit for governing the extent of movement of said switch, and means operative during the movement of said switch for revertively controlling said sending mechanism, said first named means being rendered quick to release over a fundamental circuit of upwards of fifteen miles in length when a releasing condition is established in said circuit at said sending mechanism. 95 100 105

2. In a telephone exchange system, a calling line, selective switches and a connecting circuit for extending a connection from said line, a sending mechanism for controlling said switches, a fundamental switch controlling circuit comprising said connecting circuit extending between said sending mechanism and said switches, a line relay associated with one of said switches controllable over said fundamental circuit, a control relay under the control of said line relay for governing the extent of movement of said switch, and means operative during the movement of said switch for revertively controlling said sending mechanism. 110 115 120

3. In a telephone exchange system, a calling line, selector switches and a connecting circuit for extending a connection from said line, a sending mechanism for controlling said switches, a fundamental switch controlling circuit comprising said connecting circuit extending between said sending mechanism and said switches control means at said sending mechanism, and a line relay asso- 125 130

- ciated with one of said switches controllable over said fundamental circuit, a control relay under the control of said line relay for governing the extent of movement of said switch, and means operative during the movement of said switch for intermittently operating said control means.
4. In a telephone exchange system, a calling line, selector switches and a connecting circuit for extending a connection from said line, a sending mechanism for controlling said switches, a fundamental switch controlling circuit comprising said connecting circuit extending between said sending mechanism and said switches, control means at said sending mechanism and a line relay associated with one of said switches controllable over said fundamental circuit, means under the control of said line relay for governing the extent of movement of said switch, means operative during the movement of said switch for intermittently operating the control means at said sending mechanism, and means also operative during the movement of said switch to maintain said switch controlling means operated until said switch completes its selective movement.
5. In a telephone exchange system, a calling line, selector switches and a connecting circuit for extending a connection from said line, a sending mechanism for controlling said switches, a fundamental switch controlling circuit comprising said connecting circuit extending between said sending mechanism and said switches, a stepping relay at said sending mechanism and a line relay associated with one of said switches controllable over said fundamental circuit, a control relay under the control of said line relay for governing the extent of movement of said switch, means operative during the movement of said switch for intermittently operating said stepping relay, and means also operative during the movement of said switch to maintain said control relay operated until said switch completes its selective movement.
6. In a telephone exchange system, a calling line, selector switches and a connecting circuit for extending a connection from said line, a sending mechanism for controlling said switches, a fundamental switch controlling circuit comprising said connecting circuit extending between said sending mechanism and said switches, a stepping relay at said sending mechanism, and a line relay associated with one of said switches controllable over said fundamental circuit, a control relay under the control of said line relay for governing the extent of movement of said switch, a commutator for said switch, a wiper for engagement with said commutator during the movement of said switch for intermittently shunting said stepping relay, and a second wiper for engagement with said commutator to maintain said control relay operated until said switch completes its selective movement.
7. In a telephone exchange system, a calling line, a selector switch, another selector switch and a connecting circuit for extending a connection from said line, a switch controlling circuit including said connecting circuit extending to said first named switch, a second control circuit extending between said switches, means at said first named switch for repeating control impulses from said first named controlling circuit to said last named control circuit, said means being quick to release over a switch controlling circuit of upwards of fifteen miles in length when a releasing condition is established in said circuit and means at said first named switch for repeating re-vertive impulses from said last named control circuit to said first named controlling circuit.
8. In a telephone exchange system, a calling line, a selector switch, another selector switch and a connecting circuit for extending a connection from said line, a sending mechanism for controlling said switches, a fundamental switch controlling circuit extending between said sending mechanism and said first named switch, a control circuit extending between said switches, means at said first named switch for repeating control impulses from said fundamental circuit to said control circuit, said means being rendered quick to release over a fundamental circuit of upwards of fifteen miles in length when a releasing condition is established at said sending mechanism and means at said first named switch for repeating re-vertive impulses from said control circuit to said fundamental circuit for controlling said sending mechanism.
9. In a telephone exchange system, a calling line, a selector switch, another selector switch and a connecting circuit for extending a connection from said line, a sending mechanism for controlling said switches, a fundamental switch controlling circuit extending between said sending mechanism and said first named switch, a line relay associated with said first named switch controllable over said fundamental circuit, a control circuit extending to said other switch and controlled by said line relay, said means being rendered quick to release over a fundamental circuit of upwards of fifteen miles in length when a releasing condition is established at said sending mechanism, a switch controlling relay at said other switch and a pulsing relay at said first named switch in said control circuit, means at said other switch operative during the movement thereof for transmitting impulses to said pulsing relay, and means con-

trolled by said pulsing relay for revertively controlling said sending mechanism.

10. In a telephone exchange system, a calling line, a first selector, a final selector and a connecting circuit for extending a connection from said line, a sending mechanism for controlling said switches, a fundamental switch controlling circuit extending between said sending mechanism and said first selector, a line relay associated with said first selector controllable over said fundamental circuit, said means being rendered quick to release over a fundamental circuit of upwards of fifteen miles in length when a releasing condition is established at said sending mechanism a control circuit extending to said final selector and controlled by said line relay, a switch controlling relay at said final selector and a pulsing relay at said first selector in said control circuit, means at said final selector operative during the movement thereof for transmitting impulses to said pulsing relay, and means controlled by said pulsing relay for revertively controlling said sending mechanism.

11. In a telephone exchange system, a calling line, a first selector, a final selector and a connecting circuit for extending a connection from said line, a sending mechanism for controlling said switches, a fundamental switch controlling circuit extending between said sending mechanism and said first selector, a line relay associated with said first selector controllable over said fundamental circuit, a control circuit extending to said final selector and controlled by said line relay, a switch controlling relay at said final selector and a polarized pulsing relay at said first selector in said control circuit, means at said final selector operative during the movement of said final selector for transmitting impulses to said pulsing relay, and means controlled by said pulsing relay for revertively controlling said sending mechanism.

12. In a telephone exchange system, a calling line, a first selector, a final selector and a connecting circuit for extending a connection from said line, a sending mechanism for controlling said switch, a fundamental switch controlling circuit comprising said connecting circuit extending between said sending mechanism and said first selector, a stepping relay at said sending mechanism and a line relay associated with said first selector controllable over said fundamental circuit, said line relay being rendered quick-to-release over a fundamental circuit of considerable length when a releasing condition is established at said sending mechanism, a control circuit extending to said final selector and controlled by said line relay, a switch controlling relay at said final selector, and a pulsing relay at said

first selector in said control circuit, means at said final selector operating during the movement thereof for transmitting impulses to said pulsing relay, and means controlled by said pulsing relay for intermittently altering the resistance of said fundamental circuit for operating said stepping relay.

13. In a telephone exchange system, a calling line, a first selector, a final selector, and a connecting circuit for extending a connection from said line, a sending mechanism for controlling said switches, a fundamental switch controlling circuit comprising said connecting circuit extending between said sending mechanism and said first selector, a stepping relay at said sending mechanism and a line relay associated with said first selector controllable over said fundamental circuit, said line relay having a low resistance operating winding and a normally shunted high resistance winding, a control circuit extending to said final selector and controlled by said line relay, a pulsing relay in said control circuit, and means under the control of said pulsing relay for removing the shunt from said high resistance winding whereby said stepping relay is intermittently operated.

14. In a telephone exchange system, a calling line, a first selector, a final selector and a connecting circuit for extending a connection from said line, a sending mechanism for controlling said switches, a fundamental switch controlling circuit comprising said connecting circuit extending between said sending mechanism and said first selector, a stepping relay at said sending mechanism and a line relay associated with said first selector controllable over said fundamental circuit, said line relay having a low resistance operating winding, a normally shunted high resistance winding and a differential winding, a control circuit extending to said final selector controlled by said line relay, a pulsing relay in said control circuit, and means under the control of said pulsing relay for removing the shunt from said high resistance winding whereby said stepping relay is intermittently operated and for associating said differential winding with said fundamental circuit.

15. In a telephone exchange system, a calling line, a selector switch and a connecting circuit for extending a connection from said line, a sending mechanism for controlling said switches, a fundamental switch controlling circuit comprising said connecting circuit extending between said sending mechanism and said switch, a stepping relay at said sending mechanism and a line relay associated with said switch controllable over said circuit, said line relay having a low resistance operating winding, a normally shunted high resistance winding and a differential winding, means at said sending

- mechanism for opening said circuit, and means at said switch for alternately removing the shunt from said high resistance winding and for associating said differential winding with said circuit whereby the resistance of said circuit is intermittently increased to operate said stepping relay and whereby said line relay is rendered quick to release upon the opening of said circuit at 10 said sending mechanism.
16. In a telephone exchange system, a calling line, a selector switch for extending a connection from said line, a control relay for said switch, an operating circuit for said relay, said relay having a low resistance operating winding, a normally shunted high resistance winding and a differential winding, and means at said switch for alternately removing the shunt from said high 15 resistance winding and for associating said differential winding with said operating circuit whereby said low resistance and high resistance windings are connected cumulatively in series in said operating circuit and 20 whereby said differential winding is connected in series with said high resistance winding and in opposition to both of said other windings.
17. In a telephone exchange system, a calling line, a selector switch for extending a connection from said line, a control relay for said switch, an operating circuit for said relay, said relay having an operating winding and a differential winding, and 25 means at said switch for intermittently ren-
- dering said differential winding effective whereby said relay is rendered quick to release upon the opening of said operating circuit.
18. The method of stopping an automatic switch at a desired position which switch is controlled from a distant control point over a cable loop, which consists in transmitting progress impulses from said switch to the control point, transmitting a stopping order from the control point to said switch early enough to allow for the greatest lag of a long cable, rendering the controlling means of said switch sensitive to said stop order and insuring the movement of the switch to 40 the desired position independent of the controlling means.
19. The method of stopping an automatic switch at a desired position which switch is controlled from a distant control point over a cable loop, which consists in transmitting progress impulses from said switch to the control point, transmitting a stopping order from the control point to said switch early enough to allow for the greatest 45 lag of a long cable, rendering the controlling means of said switch sensitive to said stop order and insuring the movement of the switch to the desired position if the stop order arrives before the switch has reached 50 the desired position.
- In witness whereof, I hereunto subscribe my name this 28th day of December A. D., 1920.

LEWIS H. JOHNSON.
